Application January 30, 1948, Serial No. 5,392

1 Claim. (Cl. 248—149)

1

This invention relates to improvements in stands or supports, and more particularly to the provision of stand for supporting articles such as water jugs, bottles, and other receptacles.

At picnics, races, and similar outings, it is desirable to support water jugs, baskets or the like above the ground, and it is an object of the invention to provide a simple stand or support provided with means for stably holding a jug, basket or the like.

Many times the outing is on a hill or inclined surface, and it is a further object of the invention to provide a stand having adjustable legs to enable the supporting of a jug or basket in a horizontal position on an inclined surface.

A further object is to provide a stand to support jugs above the ground sufficiently to avoid the necessity of lifting or tilting a jug to fill a receptacle.

These and other objects are attained by the novel construction and arrangement of parts hereinafter described and illustrated by the following drawings, forming a part hereof, and in which:

Fig. 1 is a side elevational view of a device embodying the invention.

Fig. 2 is a plan view of the top portion of the device.

Fig. 3 is a side view of the jug holding portion shown in Fig. 2.

Fig. 4 is an elevational view showing the stand supporting a jug or other article.

Referring to the drawings, the device is shown to comprise a circular ring 10 having attached thereto a plurality of tubular supporting legs 11, which are attached to the ring 10 by means of rivets 12, bolts or other suitable means. Connected to the ring 10 are U-shaped bands 13, which serve as a base to support a jug or other article, there being two bands 13, but there may be more if desired.

The legs 11 are provided with longitudinal slots 16 which communicate with a plurality of transverse slots 15 in which may move set screws 14. Telescoped in the legs 11 are rods 17 to which the set screws 14 are attached, the set screws being movable in the longitudinal slot 16.

As shown in the Fig. 3 the jug or article holding

2

base has the U-shaped members which include the horizontal portions 13 and the vertical portions 18.

In operation, the rods 17 can be moved in and out of the tubular legs 11 by positioning the set screws in the slot 16. After the rods have been adjusted to the desired length to properly support the stand on an inclined surface, they are turned so that the set screws move into the proper slot 15, after which the screws 14 can be tightened to hold the device in a stable condition.

From the above description it will be seen that there has been provided a simple and effective device for supporting jugs, baskets, and the like in a horizontal position on uneven surfaces. The device is preferably made of metal, but can obviously be made of other suitable materials.

The above description is to be considered as illustrative and not limitative of the invention of which modification can obviously be made without departing from the scope of the appended claim.

The invention having been described, what is claimed is:

25 A stand, comprising a pair of U-shaped members connected together at their centers, a circular ring attached to the free ends of said members, a plurality of tubular legs attached to said ring, rods telescoped in said legs, said legs having a plurality of spaced notches opening into longitudinal slots, and thumb screws movable in said slots and notches to clamp the rods to the legs at adjusted positions.

ROSS J. CAMPAGNA.
